ELECTRIC SCISSORS

Edward J. Wiggins, Chicago, Ill., assignor to
American Supercraft Corporation, Chicago, Ill.,
a corporation

Application September 25, 1940, Serial No. 358,364

2 Claims. (Cl. 30—228)

My invention relates to an electrically operated device of the vibrator type constructed to operate as a pair of scissors.

Among the objects of my invention is to provide 5 an electric scissors for cutting paper, silk, cotton, wool and other light and heavy materials; and such other objects, advantages and capabilities as will later more fully appear and which are inherently possessed by my invention.

10 While I have shown in the accompanying drawing a preferred form of my invention, yet I wish it understood that the same is susceptible of modification and change without departing from the spirit of my invention.

15 Referring to the drawing, Fig. 1 is a front elevational view of my invention; Fig. 2 is a front elevational view of my device with the cover removed; Fig. 3 is a perspective view of my complete scissors head; Fig. 4 is a detailed sectional view of my invention shown on line 4—4 of Fig. 1; Fig. 5 is a top plan view of my invention.

The embodiment selected to illustrate my invention comprises a hollow casing 10, preferably of two parts, in which is housed a vibrator mechanism 11 having a coil 12 and a plurality of E shaped laminations 13. The core 14 of said laminations 13 extends within the hollow portion of said coil 12.

19 A resilient supporting bracket 15 is attached to 30 said laminations 13 and also to armature 16.

A lead wire 17 is attached at one end to terminal 18 of coil 12 and leads at its other end through the casing 10 to an electrical source of supply. Another lead wire 19 is attached at one 35 end to a stationary switch member 20 which is attached to an L shaped insulated member 21 which rests on and is attached to laminations 13. The other end of lead wire 19 leads through casing 10 to an electrical source of supply.

40 A coil terminal 22 connects coil 11 and switch support 23 which is attached to L shaped insulated member 21. Switch support 23 has a movable contact blade 24 positioned adjacent an extension 25 of stationary switch member 20, but 45 normally spaced therefrom.

In casing 10 is an opening 26 adapted to receive the collar 27 of push member 28. The collar 27 has a circular groove 29 which receives the wall of the casing 10. Push member 28 has 50 a shank 30 on which collar 27 is slidably mounted. Push button member 28 also has a head 31. My head 32 comprises a bracket 33 which is provided with a central portion 34 connecting two end portions 35 bent substantially at right angles 55 thereto.

To attach my head 32 I provide a pair of oppositely disposed slots 36 within casing 10 and on opposite sides thereof. Within slots 36 are perfectly fitted nuts 37 having screw threaded aperture 38. End portions 35 of bracket 33 are fitted within notches 39 on either side of casing 10 and have a screw aperture 40. Screws 41 pass through said apertures 40 and 38.

Extending outwardly from bracket 33 and integral therewith is a stationary member 42 having an upper and inner edge 43 sharpened at a shearing angle as shown in Fig. 3. Pivots attached to stationary member 42 by pin 44 is movable member 45, which has an upper inner edge 46 also sharpened at a shearing angle as 15 shown in Fig. 3.

A right angle and integral extension 47 of movable member 45 lies against the upper edge of the casing and has an opening 48 to receive the extension or vibrating shaft 49 of the armature 16.

The central portion 34 of bracket 33 has a raised portion 50 extending above extension 47 and the upper end of vibrating shaft 49 and serving as a guard therefor.

In use let us assume the device has been plugged into an electrical source of supply having an alternating current. The user pushes the head 31 of push button member 28. This moves the shank 30 against movable blade 24 which in turn moves against extension 25 of stationary switch member 20 completing the electrical circuit and moving armature 16 in one direction. The resilient property of supporting bracket 15 causes the armature to move periodically in the other direction. This provides a vibrating movement of the armature 16 and its vibrating shaft 49 causing movable member 45 to move in relatively to stationary member 42. Articles such as paper, silk, wool or any other similar fabrics or materials placed between said members 45 and 42 will be cut along desired lines.

Upon the release of pressure from head 31 of push button member 28, the resiliency of movable switch blade 24 causes it to move away from stationary switch member 20, thus breaking the electrical circuit and stopping the operation of the device.

Having thus described my invention, I claim:

1. In an electrically operated scissors having a 50 casing, an electro-magnetic mechanism housed within said casing and connected to an electrical source of power, an armature positioned within said casing to receive vibratory action from the electro-magnetic mechanism, a stationary scis- 55

sors blade attached to and extending beyond the casing and a movable scissors blade pivoted to the stationary scissors blade and connected to and movable by the armature, a switch mechanism comprising a stationary member positioned within the upper portion of said casing, a resilient movable member positioned within the upper portion of said casing adjacent said stationary member, and normally spaced therefrom, a push 10 button member attached to said casing at its upper and forward portion, said push button member manually operable from the exterior of the casing, and extending within said casing to contact said movable member, said push button 15 member adapted upon being pressed from the outside of the casing to move said movable member into contact with said stationary member to complete the electric circuit and cause the scissors to operate, said movable member adapted 20 by its resiliency upon pressure being released from the push button member to return the movable member to normal spaced relation from said stationary member to stop operation of the scissors.

25 2. In an electrically operated scissors having a

casing, an electric driving mechanism housed within said casing and connected to an electrical source of power, scissors blades attached to and extending beyond the casing and operable by said electric driving mechanism, a switch mechanism 5 comprising a stationary member positioned within the upper portion of said casing, a resilient movable member positioned within the upper portion of said casing adjacent said stationary switch, and normally spaced therefrom, a push 10 button member attached to said casing at its upper and forward portion, said push member manually operable from the exterior of the casing and extending within said casing to contact said movable member, said push button member 15 adapted upon being pressed from the outside of the casing to move said movable member into contact with said stationary member to complete the electric circuit and cause the scissors to operate, said movable member adapted by its re- 20 siliency upon pressure being released from the push button member to return the movable member to normal spaced relation from said stationary member to stop operation of the scissors.

EDWARD J. WIGGINS. 25
